2 Sheets-Sheet 2

UNITED STATES PATENT OFFICE.

JOHN LOFGREN, OF CHICAGO, ILLINOIS, ASSIGNOR TO RALCO MANUFACTURING COMPANY, OF CHICAGO, ILLINOIS, A CORPORATION OF ILLINOIS.

ELECTRIC SWITCH.

Application filed February 14, 1928. Serial No. 254,263.

My invention relates to electric switches and more particularly to such a switch adapted for use in the engineer's cab of a locomotive, although its installation in other places is contemplated.

One of the objects of my invention resides in providing an extremely rugged and strong switch which is at the same time compactly arranged for controlling not only the front and rear head lights of the locomotive but also the engineer's light located in the cab and more commonly known as an order lamp.

Still another object of my invention resides in providing such a switch mechanism wherein the switch for controlling the engineer's light or order lamp is mounted directly within the same housing which encloses the switch contacts for the head lights of the locomotive whereby pronounced compactness in construction, convenience in operation and assembly of parts, and ruggedness and water-proof qualities for the switch are secured.

Still another object of my invention resides in providing such a switch with an insulating block carrying a plurality of notches at its periphery adapted to receive radially and inwardly extending stationary contacts for cooperation with a centrally disposed rotor and which notches are so arranged in spaced apart relation and are of greater number than the stationary contacts used so that various arrangements or groupings of these contacts with relation to the rotor may be availed of whereby to secure various hook-ups or wirings or combinations of the illumination of the various lamps and this construction includes an arrangement whereby certain of these notches are used for the detachable insertion of auxiliary contacts adapted to cooperate with the engineer's lamp switch mounted on the housing whereby pronounced compactness and facility of arrangement and assembly of parts is secured. An ancillary object of this feature of my invention resides in the ar-

rangement of both inwardly extending contact fingers for cooperation with the switch rotor and also these auxiliary contacts for cooperation with the engineer's lamp switch in certain of these spaced apart notches on the insulating member within the housing whereby the single block of insulation forms a common base for both sets of switches and whereby a single housing encloses and supports the operating member of the rotor and also the engineer's lamp switch.

Yet another object of my invention resides in the details of construction wherein the engineer's lamp switch may be readily installed on my prior existing switches which do not have this auxiliary switch, simply by boring or forming a hole at a proper place in the housing and fastening the movable member of the engineer's lamp switch thereto so that the portion thereof which projects into the housing is in position to cooperate with detachable contact clips insertable in certain of the notches on the insulation block of my former switch construction whereby convenience and economy in assembly and construction and operation is secured.

These and other objects of my invention will be apparent from a perusal of the following specification when taken in connection with the accompanying drawings wherein:

Figure 1 is a front view of my improved switch with the cover secured in position;

Figure 2 is a plan view with the cover removed;

Figure 3 is a section on line 3—3 of Figure 2;

Figure 4 is a modified installation of the device shown in Figure 2;

Figure 5 is a section on line 5—5 of Figure 4;

Figure 6 is a diagrammatic view of the wiring diagram used in connection with the construction shown in Figures 2 and 3 and showing only one position of the switch; and

Figures 7 to 12 inclusive are diagrammatic charts showing various positions of the switch mechanism shown in Figures 3 and 4.

Referring now to the drawings in detail, the improved type of switch shown generally in the figures is illustrated and described and claimed in my prior Patent No. 1,648,022, of November 8th, 1927 and for which an application for re-issue has been filed January 27th, 1928, Serial No. 250,026. In the former patent the engineer's lamp or order lamp hereinafter described, is not disclosed. Otherwise the construction of the other portions of the switch are identical.

As set forth in my former Patent No. 1,648,022, my switch comprises a relatively small and preferably cast iron housing 10 having opposed laterally extending lugs 12 and 14 from its opposite sides which lugs are provided with threaded openings 16 for the attachment of conduit containing tubes 18 forming a part of the electrical circuit. In addition, the upper flat wall of the housing 25 is provided with cast iron lugs 20 to which may be detachably secured the usual resistance bracket, well known in this type of switch. In addition, the basal portion of the housing is provided with a relatively flat flange 22 extending laterally on each side thereof and formed with bolt or screw openings 24 so that the housing may be securely bolted to a convenient bracket within the cab of the locomotive. In general, it might be stated that due to the lack of space within the engineer's cab, it is highly essential to provide a very compact switch construction and it is also highly essential due to the rigorous and severe usage to which these switches are subjected that they be very ruggedly constructed. It is also of prime importance that they be made so that in case of injury to parts, that such parts may be easily and quickly replaced. Furthermore, due to the fact that the operators in washing the cabs generally turn the wash upon the interior of the cab, it is absolutely necessary that these switches be made water-tight. In my present invention I have provided a construction embodying all of these advantages and in addition I have provided a construction, the essential virtue of which resides in the arrangement of the heretofore mentioned separate switch for the order lamp or engineer's lamp directly upon and within the housing of the main portion of the switch whereby such housing not only supports both operating switches and encloses them but in the present instance, I preferably utilize the insulation block which holds the contacts of the main rotor switch for also mounting the auxiliary contacts of the order lamp switch and in a manner such that the system of notches and stationary contacts

on the former are availed of for mounting the latter contacts, all as hereinafter described.

The housing 10 is provided with an upstanding flange 26 preferably of rounded formation at the side opposite to which the lugs 20 are secured and I mount within the housing formed by the flange 26, a preferably circular and preferably one piece block of insulation formed so as to provide an upstanding peripheral flange 28 and a concentrically within countersunk portion 30 forming a well or circular recess. The upstanding flange 28 is formed with a plurality of spaced apart notches 32 which extend radially inwardly and are provided with parallel sides 34 and a transversely disposed bore 36. Certain of these notches are deeper than the others and extend clear down to the upper face of the top surface of the counter-sunk portion or end 30 and these latter notches such as 38, have fastening bolts or screws 40 passing therethrough and through registering holes in the base of the housing 10 so that the insulating block 28 is securely and detachably mounted within the housing. The other notches 32 are not as deep as the notches 38 but they may be as deep if desired. These notches 32 are spaced apart about the periphery of the block and in a manner so as to receive inwardly extending stationary contact strips 42, preferably formed of strips of conducting material and the number of notches is preferably greater than the number of contact strips 42 that are used so that various combinations for the different lighting circuits may be arranged, since the contact strips 42 have also parallel sides that snugly fit within the notches 32 and may be held in such position by means of a single binding post 44 which passes through the insulating base.

At one portion of the arcuate periphery of the insulating block 28, I locate two of the notches 32 in spaced relation and on opposite sides of one of the deeper notches 38. This arrangement is shown clearly in Figures 2 and 3 of the drawings. This pair of notches is indicated at 32' on the drawings. These two notches 32' are arranged in the general organization and arrangement of the other notches 32 so that when the stationary contact strips are mounted therein and in other of the notches 32 various arrangements of the head light, including the front and rear head lights of the locomotive, may be availed of when the rotor is turned. This rotor 46 includes upper and lower sector like sheet metal contacts 48 which are spaced apart so as to wipedly engage on the upper and lower faces of the inwardly extending stationary contacts 42 and the rotor has connected thereto an in-

sulating member, preferably an upstanding block 50, adapted to be embraced by forked extensions of a turning handle 52 mounted on the cover 54 of the housing which cover 5 is detachably connected to the housing by means of screws 56 passing through threaded openings 58 in the housing. As explained in my prior patent, the axis of this handle 52 is in direct line with the axis 10 of rotation of the rotor 46 and it detachably connects with the insulation blocks 50 so that when the cover 54 is removed, the clutching connection between the handle and the rotor will likewise be disconnected. 15 The details of the construction of this handle and rotor are claimed in my prior patent and in the re-issue application thereof.

In the construction shown in Figures 2 and 3 of the drawings, the important feature of my present invention resides in mounting the engineer's lamp or order lamp, directly upon the housing 10 and in a manner such that its operable member may make and break contact with certain stationary contacts mounted within the housing and preferably mounted directly upon the insulation block 28 and preferably mounted directly within certain of the notches of this insulation block. The details of construction of this switch are set forth and claimed in my pending application, No. 66,141, filed November 2, 1925, but the manner in which this switch cooperates with the housing 10 and particularly the manner with which it cooperates with the main rotary switch within the housing and the insulating member 28 therein, and particularly the notches therein such as 32', forms the subject matter of my present invention herein since the same was not disclosed in my prior pending application 66,141. In general, the switch comprises a housing 60 of substantially cylindrical form having relatively flat substantially curved 45 and oppositely extending wings 62 and 64 which are bored to receive screws 66 engaging the curved wall 68 of the housing. The housing 68 is bored intermediate the screw openings to receive therethrough a shaft 70 of the turnable member of the switch and this shaft 70 as shown in my application 66, 141, is usually connected to a turning handle 72 carrying an integral locking collar or lugs 74 adapted to cooperate with correspondingly shaped locking lugs 76 on the barrel portion 60 of the switch so that whenever the handle 72 is turned it may be held in turned position. As shown in Figure 3 of my prior pending application 66,141, the inner end of the shaft 70 carries a plurality of washer-like contact elements 78 of insulation and a centrally disposed bridging element 80 of conducting material. The insulation elements 78 are wider than the

bridging element 80 in one of their planes 65 of rotation whereas the bridging element 80 is wider than the insulating washers in another plane of rotation so that in the position shown in Figure 2 the wider part of the insulating washer 78 will rest in contact 70 with the spaced apart contact clips herein-after described whereas the outer portions 82 of the bridging element will be out of contact but when the switch handle 72 is turned, the narrower portions of the insulating washer 78 will be brought opposite the contact clips and the wider portion 84 of the bridging element will come opposite the contact clips so as to make contact there-across or as shown in Figure 4 of my prior 80 pending application.

The contact clips hereinbefore mentioned comprise resilient metal contacts 86 and 88 having angular disposed basal portions 90 fitting snugly and lying within the notches 32' and these portions 90 have adjoining angularly bent portions 92 adapted to overlie the upper face of the flange 28 and thence to extend upwardly in spaced apart relation. These strips 90 are perforated so as to receive 95 therethrough the binding posts 94 which are held in place by the usual nuts 96 and lock washers 98 so as to provide permanent leads to the wiring system. As shown in the diagram, these clips 88 are connected by means of wires 90 and 92 to the engineer's light and to an arcuate strip 94 which connects both to a stationary strip 42 and to one terminal of the generator by means of a wire 96. The other terminal of the generator 100 connects by means of an appropriate wire 98, by means of a common wire 100 to the other terminal of the engineer's light 102, a terminal of the rear head light 104, and a terminal of the front head light 106, all as 105 shown in Figure 6. The other terminal of the rear head light connects by means of a wire 108 to one of the stationary contact strips 42 and the other terminal of the front head light connects by means of a wire 112 110 to another one of the stationary strips 42.

In certain installations, for instance for engines using 250 watt head light globes, I provide additional wiring setups or arrangements by using the notches 32' for two sets 115 of contact strips. For instance, in the installation shown in Figures 4 and 5 and shown by charts in Figures 7 to 12 inclusive, various additional wiring diagrams and arrangements may be effected. In this instance, the notches 32' are used for mounting therein both the contact clips 86 and 88 and also the stationary contact strips 42. This is accomplished by mounting therebetween an appropriate insulation member 114 and by using the common binding post 116 for holding these clips in position as heretofore described. In this instance, separate leads 120

from the clips 88 and from the stationary contacts 42 are used to the wiring diagram as will be clearly shown in Charts 7 to 12 inclusive. The charts are self explanatory since the heavy lines illustrate those which are carrying the current and from this chart it will be seen that a number of very convenient arrangements may be secured. In these charts the relatively thin lines illustrate circuits in which no current is flowing; the relatively heavy lines indicate circuits in which 32 volt current is flowing; and the dotted heavy lines indicate circuits in which 16 volt current is flowing. With regard to Figure 6, it will be understood of course, that at least six different arrangements of the stationary contact strips 42 and the rotor may be secured, corresponding to positions where no lights are burning, where the engineer's light is burning, where the front head light is burning dim, where the front head light is burning bright, where the rear head light is burning dim, and where the rear head light is burning bright.

From the foregoing, it will be seen that I have provided a very improved construction of head light switch, wherein the common housing is formed with a bore or opening and carries a bracket or bridge on its outer surface upon which is mounted the turnable member of the engineer's lamp switch and the inner end of this turnable member is arranged so as to cooperate with stationary clips carried by an insulation member within the housing and preferably by the common insulation member upon which the rotor and its stationary contact elements are mounted. In particular, by my present construction, I am enabled to utilize the arrangement of notches in which the stationary contacts are mounted, to also seat the contact clips for the engineer's lamp and I am also enabled by my construction to utilize common notches for seating both the clips and the stationary contacts and to hold them in position by means of a common binding post through the agency of a suitable disposition of the insulating material between the different clips, there being separate leads from the separate sets of contacts. It will be further appreciated that this present arrangement permits the conversion of such switches which have not heretofore been provided with switches for engineer's lamps in a very simple manner and this by boring the opening in the housing and attaching the bracket portion 62 thereto. From this construction, it will be seen that I provide a compact switch wherein both of the switches are housed in a waterproof and very rugged manner and which construction permits of the ready replacement of parts of the separate switches without damaging either or any of the switch parts.

Having thus described my invention, what I claim as new and desire to secure by Letters Patent is:

1. In a locomotive head light switch, the combination of a housing, insulating means therein having stationary contacts arranged to extend inwardly about a common center, a rotor turnably mounted about said common center and adapted to electrically connect the various combinations of said contacts for illuminating the head lights and an auxiliary switch for illuminating the engineer's lamp, said switch being mounted directly on said housing and having a shiftable portion extending through the wall of the housing and adapted to make and break contact with contacts mounted within and insulated from said housing.

2. A combined locomotive head light switch and engineer's lamp switch comprising a common housing adapted to receive a mounting of insulation carrying stationary contacts arranged about a common center, a rotor in said housing adapted to make and break different arrangements of said contacts, a pair of auxiliary switch contacts mounted on said insulation, and an auxiliary switch mounted on said housing and having a shiftable member passing through the walls thereof and adapted to cooperate with certain of the contacts on the insulation member.

3. In a device of the class described, the combination of a housing, a block of insulation therein having an up-standing flange provided with radially extending notches, an auxiliary switch mounted on said housing and having a shiftable member extending radially of the insulation block and intermediate two of the notches on said insulation block, contact clips mounted in said spaced apart notches and a contact member carried on the inner end of said switch adapted to make and break contact with said contact strips, and a rotor adapted to contact with said stationary contact strips.

4. In a device of the class described, the combination of a housing, a circular block of insulation mounted therein and provided with a peripheral upstanding flange formed with radially extending spaced apart notches, a plurality of flat contact strips mounted in said notches, said notches being of greater number than said strips, said upstanding flange forming a peripherally counter-sunk well, a rotor mounted in said well and adapted to make and break contact with said contact strips, an auxiliary switch mounted in said casing and having a shiftable portion extending therethrough and over the upstanding notched flange of the insulation block and provided with a bridging element, said upstanding flange having a pair of notches disposed at an equal distance on op-

posite sides of said bridging element and a contact strip mounted in each of said notches and arranged to be engaged by said bridging element.

5. In a device of the class described, the combination of a housing, an insulation member therein having a plurality of notches disposed about a common center, certain of said notches having inwardly and radially extending contact strips located therein, a rotor mounted about the common center of said contact strips to make and break connection with said strips, an auxiliary switch carried by said housing and having the movable portion passing through the wall thereof provided with a contact member on its inner end, certain of the contact notches of said insulation block being disposed adjacent to the inner end of said auxiliary switch and auxiliary contact members mounted in said notches and adapted to cooperate with the member on the inner end of said switch.

6. In a device of the class described, the combination of a housing, an insulation member therein having radially extending notches spaced apart about a common center, a rotor turnably mounted about said common center, contact strips in certain of said notches for engagement with said rotor, an auxiliary switch including a shiftable member carried by said housing and having a portion carrying a contact disposed within said housing, said insulation member having a pair of spaced apart notches disposed on opposite sides of the inner end of the shiftable member of said rotary switch, additional contact strips mounted in said pair of notches and adapted to be contacted with said rotor, insulation means also in said pair of notches and auxiliary switch contact strips also in said notches and adapted to be contacted by the contact member of the shiftable portion of said auxiliary switch and a binding post adapted to hold respective contacts in said notches.

7. In a device of the class described, the combination of a housing, a circular block of insulation in said housing and having an upstanding flange provided with spaced apart radially extending notches having parallel side walls, contact strips mounted in certain of said side walls and secured therein by a single binding post, said contact strips having parallel sides snugly fitting in said notches, an auxiliary switch mounted on said housing and having an actuatable portion passing through the wall thereof radially of said insulation block and carrying a contact bridge, said insulation block having two of said notches arranged in spaced apart relation on each side of the bridging member and resilient contact strips having basal portions mounted in each of said pair of notches and provided with angular bends therein over-lying the peripheral flange ad-

jacent the notches, with the free edges of said strips extending upwardly on each side of the bridging member whereby on movement of the actuatable member of said auxiliary switch, said contacts may be made or broken.

8. In a device of the class described, the combination of a housing, an insulation block mounted therein and having an upstanding flange provided with a plurality of spaced apart radially extending notches having parallel side walls, a rotor mounted in the common axis of said notches, a plurality of stationary contacts mounted in certain of said notches and adapted to be engaged by the so rotor, an auxiliary switch carried by the housing and having an actuatable portion extending therethrough and carrying a contacting bridge normally located adjacent the notched flange of the insulation member, said notched flange having a pair of notches, one each being disposed on each side of the bridging member, a resilient sheet metal clip having a basal portion snugly fitting in the notches and having an upward bend and a lateral bend over-lying the adjacent top portion of the flange and having an upstanding extension of resilient character whereby to provide resilient spaced apart contacts lying on each side of the bridging member and a binding post passing through the basal portion of each of said contact members and through the notch in the insulating block to hold the same in position.

9. In a device of the class described, the combination of a housing, an insulation block therein, said block having an upstanding flange provided with laterally extending notches in spaced apart relation about a common center, a rotor mounted in said common center for contact with stationary strips mounted in certain of said notches, an auxiliary switch carried by said housing and having a rotatable member extending over the upstanding flange of said insulation block and provided with an insulating member and an adjacent bridging member, said members having portions of varied diameters angularly disposed with respect to each other, said upstanding flange of the insulation member having a pair of notches, one lying on each side of the inner end of the actuatable member of the auxiliary switch, said notches having parallel sides, and spring clips, each clip having a basal portion snugly fitting in the notch and having a lateral portion forming an upstanding resilient finger, binding posts passing through the basal portion of the clip and through the insulation member to hold the clip in place, the arrangement being such that on rotation of said auxiliary switch, said bridging member will be brought into and out of contact with the opposed resilient clips.

10. In a device of the class described, the

combination of a housing carrying a block of insulation having inwardly extending stationary contacts, a rotor adapted to make and break contact therewith, said casing being constructed and arranged to provide a hole, a bracket carrying a shaft passing through said hole, said bracket being attached by means of screws to the outer portion of said casing, said bracket having a

locking means and the handle of said shaft having cooperative locking means, said shaft carrying a bridging element on its inner end and contact clips carried by said insulation block adapted to be made and broken by movement of said shaft.

In witness whereof, I have hereunto subscribed my name.

JOHN LOFGREN.
